UNITED STATES PATENT OFFICE.

KARL F. KIRKMAN, OF ROCKFORD, ILLINOIS, ASSIGNOR, BY MESNE ASSIGNMENTS, TO AUTOMATIC PRESS FEEDER COMPANY, OF CHICAGO, ILLINOIS, A CORPORATION OF ILLINOIS.

PRINTING PRESS

1,031,345.

Specification of Letters Patent.

Patented July 2, 1912.

Application filed January 19, 1909. Serial No. 473,171.

To all whom it may concern:

Be it known that I, KARL F. KIRKMAN, a citizen of the United States, formerly residing at Chicago, in the county of Cook and State of Illinois, but now residing at Rockford, in the county of Winnebago and State of Illinois, have invented certain new and useful Improvements in Printing Presses, of which the following is a specification:

My invention relates to printing presses and the object thereof is to provide novel and efficient automatic means for automatically stopping the machine in case of improper feeding or a lack of feeding of the paper.

My invention may be incorporated in a new printing press as an integral part thereof, or may be built as an attachment to be applied to printing presses already in use, the same being particularly applicable to presses of the Gordon type.

The various features of novelty and utility in my invention will be made apparent by the description hereinafter given.

In the drawings, Figure 1 is an elevation of one side of a considerable portion of the well-known Gordon press showing my invention incorporated therewith as an attachment; Fig. 2 an elevation of the other side of such press; Fig. 3 a front elevation of such attachment; Fig. 4 a vertical sectional elevation taken on a line just within one of the side frames of the machine; Fig. 5 a similar view as to the upper portion of the mechanism or attachment but on a larger scale; Fig. 6 a plan view of the machine; Fig. 7 a sectional elevation on the line 7—7 of Fig. 15; Figs. 8 to 11 detail views of a portion of the mechanism illustrated in Fig. 7 showing certain of the parts in different relative positions; Fig. 12 a plan view of a portion of the mechanism of Fig. 11; Figs. 13 and 14 detail views of the disks 79 and 87; Fig. 15 a plan view of the cam shafts, cams and operating levers, etc., and Fig. 16 a detail view of the gripping jaws of the transfer frame.

Referring to the present embodiment of my invention as illustrated in the drawings, I have shown the same in the form of an attachment which is applied to and mounted upon the frame 1 of the well-known Gordon printing press with the exception that the

plate 2 is instead of being movable as is

usual, is blocked or in any other suitable way made immovable, the type bed 3 which carries the type or printing form remaining movable in the ordinary way. It will be understood, however, that the particular type or style of printing press is immaterial and that my invention, as hereinbefore stated, may be built as an integral part of the printing press structure or as an attachment, but for the purposes of an understanding of my invention I will proceed to describe the same as herein illustrated and as the same is used in practice, that is as an attachment to a Gordon press modified slightly in the manner stated.

My attachment is provided with a main frame 4 forming a support for the different working parts of the attachment and secured in any suitable manner to the printing press frame 1. At the upper end of this frame 4 I mount an endless conveyer comprising a pair of transverse rollers 5 and 6 and a suitable endless belt 7. By preference this belt is made continuous from side to side and as clearly shown in Fig. 5 the same slides upon the upper surface of a support 8 located between said rollers along the top reach of the belt. This belt is adapted to receive and to slowly feed as required the pile of paper which is placed thereupon in combed form and kept in that condition and fed by such belt. For the purpose of properly feeding the paper, the endless belt is moved as required, and in suitable manner, for instance, by means of the ratchet wheel 9 operatively connected with the front roller 6 and cooperating with the pawl 10 which is mounted upon the pawl carrier 11 whose oscillation and proper timing as to movement will be hereinafter described.

The front edge of the paper is stopped by means of a cross bar 12 having a series of rearwardly-extending fingers 13 which are formed separately or integral therewith and adapted to lie in grooves formed in the belt by reason of the fact that the front roller 6 is itself provided with a series of circumferential grooves 6^a as clearly shown in Fig. 5. It will be understood that owing to the tension and pliable nature of the belt, the latter will assume the same surface character as the front roller 6. By this means the paper will be properly received and stopped by the fingers 13 and be prevented from following the belt.

For the purpose of separating the top sheets one at a time from the pile of sheets a transverse roller 14, preferably corrugated and of suitable material, such as rubber, is provided. This roller is arranged to be oscillated in contact with the top sheet of paper first in one direction and then in the other and to be slightly raised during the time that such sheet is being pulled from the pile by the feed rolls hereinafter described. In one of said oscillations this roller 14 causes the paper to buckle and because of this function I will hereinafter refer to the same as the "buckling roller." This roller 15 is journaled at its ends in bearings 15 and provided with the central shaft or axis 16. In practice this shaft is connected at one end with a bevel gear 17 adapted to mesh with a corresponding bevel gear 18 (Figs. 20 and 6) mounted on and driven by the vertical shaft 19 carrying at its lower end a similar bevel gear 20. This latter gear is adapted to mesh with another bevel gear 21 to which is operatively connected an oscillating crank arm 22 driven by means of operating connections hereinafter described. In order to provide for a slight vertical movement of the buckling roller a sliding connection is provided between the shaft 19 25 and either one of its bevel gears in the present instance bevel gear 18.

The buckling roller coöperates in the buckling operation with a normally fixed but adjustable transverse bar 23, extending 35 across the pile of sheets and in proximity to the top sheet thereof. The object of this roller is to cause the paper to buckle or move upwardly when the buckling roller is oscillated in a direction to move the top sheet 40 rearwardly as to its front portion. In order to accommodate sheets of different thickness this roller 23 is adapted to be adjusted toward or away from the buckling roller. To this end and as a means for supporting 45 such roller, the latter is rotatably mounted on a shaft 24 which is adjustably secured in longitudinal slots 25 formed in blocks 26 at each side of the machine, all as clearly indicated in Figs. 5 and 6. These blocks are 50 carried by and extend forwardly from a cross frame comprising the cross bar 27, preferably having on its underside a supplemental bar or piece 28 of suitable material, such as wood, adapted to press directly upon the pile of sheets. Said frame also comprises upright portions 29 located at the ends thereof and connected by the cross shaft 30. This shaft extends through 55 and is guided by substantially vertical slots 31 in an upward extension of the attachment frame 4 and the same, together with the entire cross frame, is held downwardly upon the paper with a yielding pressure by means of springs 32 arranged in said slots 31. These springs

may be adjustable in tension in any suitable manner as by means of the adjusting screws 33. In the present instance the roller 23 is held in adjusted position by the bearing shaft 24 adjustable in the slots 25 and held in adjusted position by means of the clamping bolts 34, the ends of the blocks 26 being properly slotted as clearly shown in Fig. 5 to provide for such clamping.

The cross bar 28 and the roller 23 are adapted to press upon the pile of sheets with a yielding pressure but arranged to be slightly withdrawn therefrom at the time when the top sheet after being buckled is being fed forwardly into the machine by the feed rolls in the manner hereinafter explained. To this end I provide a pair of oscillating levers 35 arranged at opposite sides of the machine as indicated in Figs. 5 and 6 with their rearward ends in contact with the underside of the vertically movable boxes or blocks 36 which slide in the slots 31 with the result that when said levers 35 are oscillated upwardly the cross bar 28 and roller 23 will be slightly raised against the tension of the springs 32. To afford proper movement to said levers, the latter are secured to the cross shaft 37, one of said levers, as shown in Figs. 4, 5 and 6, being connected by means of the link 38 to an oscillating bell crank 39 pivoted on the main frame 4. This bell-crank has a cam roller 39a which is so arranged as to coöperate with a cam 39b secured to the cross shaft 48, thereby giving the roller 14 a positive movement to and from the paper.

In front of the buckling roller is arranged a series of rearwardly-extending fingers 40 whose rearward ends extend downwardly in contact with the top sheet of paper and whose forward ends are secured to or form a part of a transverse rod or shaft 41 having an oscillating movement. During the time when the buckling roller is moving in its clockwise direction (Fig. 5) for the purpose of moving the front end of the top sheet of paper rearwardly and buckling the same, the fingers 40 are slightly raised to remove any interference with said operation but after the front edge of said top sheet of paper so being acted upon has passed to the rear of these fingers, the latter are moved downwardly upon the second sheet of paper which will subsequently become the uppermost one, with the result that in the movement of the buckling roller in the opposite direction, the front edge of the top sheet will be directed and deflected by said fingers in an upward direction and free from the pile of paper. These fingers 40 are oscillated in proper time with the other mechanisms in suitable manner and in the present instance the same is operated by means of an arm 42 secured to one end of shaft 41 and connected by means of a link 43 to one

end of a lever 44. This lever, which is pivoted at 45, is provided at its center with a cam roller 46 adapted to coöperate with and be actuated by a cam 47, secured to one of the main driving shafts 48^a of the machine.

In order to automatically keep a uniform depth of paper underneath the buckling roller, that is a uniform thickness of paper between the lower surface of such roller and the upper surface of the feed belt 7, I provide suitable means which, in the present instance, consists of mechanism controlled by the relative position of the buckling roller for actuating the feed belt. As shown, a vertical link 49 is connected at its upper end with bell crank 39, Figs. 4 and 15, while its lower end is pivoted to the lever 50, the extreme end of which is connected by means of a link 51 to the outer end 20 of the pawl carrier 11 hereinbefore described. When in the feeding of the paper the buckling roller is lowered from its normal position, the link 49 is forced slightly downwardly, by reason of its connections 25 with the bell crank 39 and link 38, with the result that the lever 50 is slightly oscillated in a clockwise direction, (Fig. 4) so that a cam roller 52 is brought into the path of travel of the cam 53 secured to the driving 30 shaft 48. When, in its rotation, this cam contacts the cam roller 52, the pawl-carrier 11 is moved upward by reason of its connection with the lever 50 through the link 51 and the pawl 10 will be caused to engage a tooth or teeth as the case may be on 35 the ratchet 9 and move the feed belt forwardly in slight degree but sufficient to move the pile of paper forwardly to provide the uniform depth of paper underneath 40 the buckling roller.

When the top-most sheet of paper is fed forwardly by the buckling roller and deflected upwardly by the fingers 40, the same will be directed between the two feed rolls 45 54 and 55, of which the former is positively driven as hereinafter explained, and of which the latter is an idler, Figs. 5 and 6. From these feed rolls the sheet of paper passes between a second pair of feed rolls 56 and 57, the former being a positively driven roll and the latter an idler. This idler is spring-pressed toward the feed rolls 56 by means of a spring 58, whose tension may be regulated by the adjusting screw 59. 55 The paper is guided to the first set of feed rolls by fingers 40 and into the second set of feed rolls by means of guides 60, Figs. 4 and 5. From the latter set of feed rolls the paper passes downwardly in an inclined 60 direction between the carrying tapes 61, the paper being presented to a transfer frame and presented thereby to the printing mechanism and subsequently delivered from the machine.

65 I will now proceed to describe the means

whereby the machine is automatically stopped whenever the feed of paper is for any reason interrupted or if the paper should be stopped or clogged in its feeding or improperly fed. Speaking generally, 70 such stop mechanism consists of a controlling means placed in the path of the sheets of paper between the feed tapes for controlling the stop mechanism proper which, in the present instance, operates an electric 75 switch controlling the power of the machine and also operates a brake which here acts upon the fly-wheel of the press.

Describing the present embodiment of my stop mechanism as herein shown, (Fig. 7), 80 I secure upon a transverse stationary shaft 62 a double lever 63 which is connected with a bell-crank gear 64 by means of link 63^a. This bell-crank gear 64 is secured to a transverse rock shaft 65 and meshes with the gear portion of a segmental gear 66 which is secured to a rock shaft 67. These gears and pinion are located adjacent among the feed tapes, near the lower end thereof, the gears being arranged at one side of such tapes. 85 The double lever 63 is provided with a cam-roller 68 which coöperates with the cam wheel 69 as hereinafter explained. Upon the rock shaft 67 is loosely mounted a bell crank 70 which has a yielding driving connection with such shaft by means of the spring 71 and the arm 72, the spring being connected by studs 73 with said arm and bell crank respectively. Such construction thus provides for a yielding lost motion. The 90 forward end of the bell-crank 70 is hollow or bifurcated (Fig. 3) and there provided with a detent 74 of irregular shape and pivoted at its central portion at 75. This detent is bell-crank shaped as to its main portion, 95 but provided at one end with a hook 76, the other end being properly weighted, as by means of the slotted arm 77 to keep the same in a normal position. The limits of movement of this detent are defined by means of 100 the stop pin 78 received by the slot in said arm. This arm is of such a length as to present the detent to the paper being fed through the machine and to cause it to contact such paper and to be oscillated thereby 105 independently of the bell-crank 70, in the manner hereinabove described. This detent is adapted to coöperate with a disk 79 loosely mounted upon the rock-shaft 65 and of the peculiar shape illustrated in detail in 110 Fig. 13. This disk is provided upon one side with a hook portion 80 and also with a substantially right-angled notch 81, while the other side of such cam is cut away or reduced at 82 for a purpose hereinabove made apparent. Such disk is kept in a normal position relative to its shaft or axis with a yielding pressure, as by means of a spring 83 secured at one end to a pin 84, and at its 115 other end to a pin 85 which is mounted on 120 the rock-shaft 65. The disk 79 is held 125 in its normal position by the yielding pressure of the spring 83. The hook portion 80 of the disk 79 is received by the slot in the slotted arm 77 and the notch 81 of the disk 79 is received by the 130

a fixed bracket 86. Upon the rock shaft 65 is mounted a second disk 87 which I will herein refer to as the positive or ratchet disk. This disk, which is illustrated in detail in Fig. 14, is loosely mounted upon this rock shaft or axis 65 and adapted to cooperate with the spring-pressed pawl 88 pivoted upon a pawl-carrier 89 that is secured in suitable manner to said rock shaft 65, detail of which pawl and pawl carrier are shown in Figs. 10 and 12. This pawl 88 is adapted to engage the notch 90 in the ratchet disk 87 when permitted to do so by the disk 79, as hereinafter explained, and to this end this pawl 88 is of sufficient width to cooperate with both disks 79 and 87 as indicated in Fig. 12. The tendency of this pawl is to engage said notch 90 but it is prevented from doing so whenever the paper is being fed and also being fed in proper manner by means of the other disk 79 which acts as an interference to the action of said pawl and therefore controls the same, for which reason I will refer to the disk 79 as the controlling disk.

Referring to the operation of the mechanism as thus far described, and assuming first that the paper is being fed properly to the machine, the parts are so timed that when the gears 64 and 66 are actuated in the manner described a sheet of paper is then being fed along the feed tapes in proximity to the bell crank 70 and its detent 74. During the feeding of this sheet the segmental gear 66 is moved in clockwise direction, that is in the direction of the arrow in Fig. 8 and the bell crank 70 is moved in the same direction. During this movement the free end of the hook 76 will come into contact with the sheet of paper and the detent, being very light in weight, will be rocked by the paper during the continued movement of the bell crank 70 as shown in Fig. 8, with the result that such detent will be retracted as to its hook end and will move upwardly to a plane above or coincident with the notch 81 of the controlling disk 79. Just as soon as the top edge of the sheet of paper has passed by said plane, the hook end of the detent will drop into said notch 81 and take its position therein as indicated in Fig. 9. Thereupon, during the reverse of the oscillation of the bell crank 70 such detent will move the controlling disk in a clockwise direction against the tension of its spring 83. During the first described movement of the segmental gear 66 the rock shaft 65 being oscillated in an anti-clockwise direction (Fig. 8) the pawl carrier 89 and its pawl 88 are oscillated correspondingly, at which time the pawl will ride upon the peripheries of both disks. In the reverse oscillation of the parts hereinbefore referred to the pawl carrier and its pawl will move in a clockwise direc-

tion and the controlling disk 79 will be moved in unison by the detent in the manner already explained, with the result that the pawl 88 will be disabled or rendered inoperative as shown in Fig. 9—in other words such pawl will be prevented from engaging in the notch 90 of the ratchet disk and the latter will therefore not be operated. The parts of the stop mechanism now being described are the controlling elements and the parts hereinafter described will not be disturbed in their said position.

Now assuming that for some reason the feeding of the paper has been interrupted and no paper is running or being fed by the feed tapes, the detent 74 will not be moved outwardly on the upward movement of the bell crank 70, as hereinbefore described, inasmuch as no paper is now running, with the result that the hook end 76 of the detent will engage the hook 80 of the controlling disk which, in the present instance, is held by spring 83 against adjustable screw 91, and the arm 72 continues to oscillate by virtue of the yielding driving connection 71. In the succeeding movements, the controlling disk 79 will not be oscillated by the detent but will be held in normal position by the spring 83 so that in the return movement of the rock shaft 65 the pawl 88 will not be interfered with by the controlling disk but at the proper time will drop into the notch 90 and in its continued movement will slightly oscillate the ratchet disk 87. As a result, the link 92 which is pivotally connected to such ratchet disk will be moved in the direction of its arrow shown in Fig. 11. This link 92 is pivotally connected at its lower end to a bell crank pawl 93, which acts as a trigger holding a lever 94 and its associated parts in the position indicated in Fig. 7. This lever and its associated parts are mounted to oscillate on the shaft 62 as an axis and the same is provided at one end with a depending lug 101 which directly cooperates with the trigger 93. This lever 94 is suitably secured to a rock shaft 96 whose upper end is provided with a lateral extension 97 carrying at its free end a stud 98 and a cam roller 99, said stud and roller being on axes at right angles to each other, Fig. 15. The cam roller 99 is located on one side of the stud 98, in position to cooperate with the periphery of the cam 100, while the stud 98 is located on the under side of extension 97 in position to cooperate with a projecting portion 101 of said cam, Figs. 7 and 15. When the trigger is operated in the manner explained the resistance against the movement of the bearing frame 102 in a clockwise direction (Fig. 7) is removed, and the same will be caused to move in such direction as soon as the cavity 103 in the cam wheel 100 is presented to the cam roller 99.

130

120

115

125

When in the rotation of the cam wheel 100 the projection 101 in the cam groove is presented to the stud 98, the shaft 93 will be rocked or oscillated with the result that the main stop rod 104 will be shifted longitudinally by reason of the operating connection afforded by the slotted rock arm 94 on the lower end of rock shaft 96 and the projection or pin 105 on the stop rod 104, which pin is received by the slot in arm 94, as indicated by dotted lines in Fig. 7. The movement of the stop rod 104 is inwardly within the main frame 4 of the machine, with the result that another pin or projection 106 thereon, Fig. 2, will move inwardly the forward end of the lever 107, said lever being fulcrumed at 108. When the lever 107 is thus moved by the longitudinal shifting of the stop-shaft 104, the rearward end of the lever 107 will contact and throw the handle 109 of an electric switch 110, here shown as an ordinary knife switch, which connects terminals of an electric circuit in which an electric motor (not shown) for driving the press is interposed. It is thus apparent that when the paper ceases to feed through the machine the electric current will be automatically cut off and the machine stopped. In order to stop the machine instantly, I prefer to have the stop mechanism also control a brake for the fly-wheel of the press and to this end I so locate the stop-rod 104 that it will normally hold the brake lever 111 in a position to retract the brake. As herein shown, this brake lever is connected by means of a link 112 with a depending arm 113, whose lower end is in position to contact a brake-shoe 114 and to drive and hold the same against the fly-wheel 115 of the press. One end of the link 112 is pivotally connected to a depending crank arm 116 and in the present instance the lower end of such arm is connected to a spring 117 which tends to draw the arm 113 against the brake-shoe but is normally prevented by the stop rod 104. It will be understood that at the moment when the stop rod 104 is withdrawn inwardly and the electric switch thereby operated, the brake-lever 111 is relieved of interference and the spring 117 thereupon moves the system of arms and causes the arm 113 to contact the shoe 114 and hold the same against the fly-wheel, with the result that the power is cut off and the machine stopped instantly.

In the event that the feedway should become clogged or a sheet of paper should become lodged therein, the stop mechanism will act to stop the machine in the same manner as when no paper is running, according to the example already explained. Under this second assumed condition, the detent 74 on its anti-clockwise movement will be prevented from engaging the cavity 81 of the controlling disk 79 by reason of

the presence of the sheet of paper A as clearly shown in Fig. 11. Consequently this disk 79 is left in its normal position and the pawl 88 is thereupon free to enter the tooth 90 of the ratchet disk 87, with the result that the machine will be stopped as already described. 70

Referring next to the driving connections for the parts described, the power is transmitted from the main power shaft 118 through the train of gears and pinions 119, 120, 121, 122, 123, 124, 125, thence through said shaft 48^a to the other side of the machine, gear 127 on said shaft and through the train of gears 128, 129, to shaft 130, on the outer end of which is secured the gear 131, thence to train of gears 132, 133, 134, 135, 136, and through the lower train of gears 137, 138, 139, 140, 141. The gear 128 is secured to the cross-shaft hereinbefore referred to and the same is provided at its outer end with a box cam 142 with which operates the roller 143 which is mounted upon the lower end of the link 144 whose upper end is pivotally connected to the crank arm 22 hereinbefore referred to. By means of this construction the buckling roller is given its oscillating movements hereinbefore described. The train of gears 131 to 136 drive the feed rolls hereinbefore mentioned. 85 90 95

The means for receiving the paper fed by the tapes down the feed-way and for transferring the same to the printing mechanism form no part of my present invention except as a part of an operative machine, but as the same are herein illustrated they may be briefly explained as follows: Describing said receiving and transferring mechanism, the paper is fed downwardly between the tapes until it comes to rest against the series 105 of stop fingers or lugs 145, which arrest its further movement temporarily and also align the same so that its lower edge is in perfect register and in proper position to be presented to the transfer device and to the 110 printing mechanism of the press. These stops are formed at the lower end of a cross piece 146 which extends transversely of the machine and is provided with rearwardly extending lugs 147 at its ends. The parts 115 described constitute a frame bodily movable to the left (Fig. 4) for the purpose of withdrawing the stops from the paper when the transfer mechanism is about to act thereupon. At the sides of this movable frame 120 parallel rods 148 are provided, the same sliding in bearings 149. This frame and consequently the stops 145 are held to their normal active position by means of the coiled spring 150 against which the frame is positively moved in the withdrawing operation by means of the bell-cranks 151 secured to the rock shaft 152 extending transversely of the machine and provided on one of its arms with a cam roller 153 coöperating with 125 130

the cam 154 for producing the desired movement of the stops 145 in proper time.

The transfer frame for transferring the paper from the stops 145 is a U-shaped frame as illustrated in Fig. 3. The frame consists of a cross member or strip 155 and two parallel strips 156 whose upper portions are in the form of rack bars. This transfer frame is adapted to move up and down in a plane parallel with and substantially coinciding with the plane of the inclined feed way, the same sliding in suitable bearings 157 on opposite sides of the machine. The cross strip 155 constitutes one of the gripping jaws for engaging the bottom edge of the paper, the second jaw consisting of a strip 158 pivoted upon said cross strip and having projections 159 forming the jaws proper adapted to coöperate with similar projections or jaw members 160 on the cross strip. The pivoted cross strip 158 is held pressed with a yielding pressure against the other strip by means of springs 161, with the result that the gripping jaws are closed under normal conditions. The lower members of the jaws are provided with a series of pins 162 acting as registering pins for the bottom edge of the paper so that the same will be gripped and held by the transfer device in proper registered position.

For deflecting the paper from the plane of its travel to the printing mechanism in order that it may be delivered at an angle to the delivery mechanism, I employ substantially the same deflecting fingers as shown in my prior application, but I so arrange and adapt the same that such fingers are given an additional function, to-wit the stripping of the paper from the platen. As shown more particularly in Figs. 1, 3 and 4, the series of fingers which are here three in number comprise two portions, a main portion 163 and a longitudinal portion 164, which is adjustable in the base portion for shortening or lengthening the fingers as required. In practice the base portions 163 are provided with longitudinal channels to receive the portions 164 which are in the form of thin strips, the same being clamped in proper adjusted position by means of the clamping screws 165. The fingers are secured to a hollow cross shaft 166 which is loosely mounted on shaft 166 and at whose ends are secured the bell cranks 167 held spring-pressed by means of the springs 168. The fingers, as well as the shaft 166, are provided with a parallel ruler motion by reason of the provision of the two similar arms 169 and 170 and the connecting link 171, the arms 169 being pivotally connected at their lower end with the cross shaft 166 and at their upper ends to the fixed point 172. The upper arm 170 is secured to the cross shaft 173 which is provided with a crank arm 174 connected by means of the link 175

which is pivotally connected to the operating lever 176. For the purpose of imparting the necessary rocking movement to such latter lever, the same is provided with a cam roller 177 adapted to coöperate with the cam wheel 178. By means of this operating connection deflecting fingers are given the desired movement toward and away from the platen, the innermost position of such fingers being illustrated by the dotted lines in Fig. 4. To obtain the additional or clamping function I provide a spring-pressed plunger 179 which is adapted to be projected at the proper moment against one of the arms of the bell crank 167, with the result that the fingers will be moved farther to the left (Fig. 4) and against the paper, thereby clamping the same against the platen to strip the paper from the type bed or form. In the present instance these plungers 179 are actuated by means of the bell cranks 180 having pin and slot engagement therewith and provided with cam rollers 181 coöperating with the cam wheel 182. The desired adjustment of the clamping action is obtained by means of the adjusting screws 183 as well as the adjustable abutment 184. The movement of the plungers is outwardly against the tension of the springs 185 which restore the same to normal position. As the transfer frame moves upwardly and is in proximity to said deflecting fingers, the latter move outwardly, to the position shown in full lines in Fig. 4 and such frame continues the position to receive and grip the bottom edge of the sheet of paper. In this upward movement of the transfer frame, the jaws thereof are opened by contact with the cam plates 186 and with the rollers 187 mounted upon the movable members of the jaws. After the transfer frame has moved below the range of the deflecting fingers the latter is moved to the dotted line position indicated in Fig. 4 and the plungers 179 thereupon rock such fingers inwardly as to their lower ends and thereby clamp the paper against the platen to strip it at the proper time. After the paper has thus been stripped from the form, the deflecting fingers are released from their clamping or stripping position and upon the continued upward movement of the transfer frame such fingers are moved outwardly to a position of non-interference, as already explained. In the forward movement of the transfer frame the top edge of the paper is deflected laterally to the left (Fig. 4) to the delivery mechanism by means of the inclined projecting portions 188. The delivery mechanism comprises in the present instance endless belts or tapes 189 and 190 and suitable pairs of rollers 191 and 192.

The transfer frame is operated in the present instance from the cross shaft 48 through a series of operating connections 130.

now to be described. To said shaft 48 is secured a crank arm 193 to which a link 194 is pivotally and adjustably connected. The upper end of the link is slotted and provided 5 therein with a sliding bearing box 195 held in its upper position by means of the spring 196. The upward limit of movement of the box is adjustable by means of the adjusting screw 197. This bearing box is pivotally 10 connected to a vertically movable rack guide 198 sliding on a guide bar 199 and meshing with a pinion 200 which in turn meshes with and drives a pinion 201 secured to a transverse shaft 202. To this shaft near its ends 15 are secured two pinions 203 which are adapted to engage the rack bar portions 204 of the transfer frame. The degree of movement of the transfer frame is adjustable to a nicety by means of the stops 205 which 20 are adjustable up and down upon the rack bars 204. The sliding bearing box 195 in connection with the spring 196 forms a yielding driving connection for following up or compensating for the movement of the 25 operating connections after the stops 205 have come in contact with and have been arrested by a fixed part of the machine frame, in the present instance the bearings 157 of the rack bars.

30 When my invention is made as an attachment to the usual Gordon press I provide suitable means for securing the same thereto and for adjusting it in proper position and in Fig. 4 I have shown a simple and efficient means to this end. As shown I provide a metallic frame 206 which is secured to the usual feed board support 1^a of the press by means of the screw bolts 207. For the purpose of adjusting or leveling the parts 206 35 and 1^a I provide adjusting screws 208. The attachment is connected to and supported by the frame 206 by a parallel ruler motion which not only permits the attachment to be moved outwardly from its operative position 40 but also is adapted to maintain the attachment in working position to which it is adjustable. As shown, parallel links 209 are pivotally connected at their lower ends to the frame 206 and at their upper ends to the 45 main frame 4 of the attachment. When the attachment is in proper working position it is secured to the frame 206 by means of the screw bolt 210 having the hand wheel 211. The attachment is properly leveled or adjusted by means of the adjusting screws 212.

I claim:

1. In combination with the paper feeding means of a printing press, mechanism movable at every operation of the press and arranged to stop the press unless interfered with, and means which under proper conditions of paper feeding interferes with such mechanism to prevent the stopping action thereof;

2. In combination with the paper feeding 65 means of a printing press, mechanism movable at every operation of the press and normally tending to automatically stop the press, and means controlled by the absence or clogging of the paper and arranged to interfere with said mechanism only when the paper is being fed or fed properly, whereby said mechanism will be rendered inoperative and the stopping of the press prevented.

75 3. In combination with the paper feeding means of a printing press, mechanism movable at every operation of the press and normally tending to automatically stop the press, and means movable in the path of the 80 paper and controlled by the absence or clogging of the paper, said means being arranged to interfere with said mechanism only when the paper is being fed or fed properly, whereby said mechanism will be 85 rendered inoperative and the stopping of the press prevented.

4. In combination with the paper feeding device of a printing press, mechanism normally tending to automatically stop the 90 press, and means adapted to control said mechanism and itself controlled by the presence of the paper, said means comprising a member arranged to be moved across the path of the paper and to render such mechanism inoperative in the proper passage of the paper.

5. In combination with the paper feeding device of a printing press, mechanism movable at every operation of the press and normally tending to automatically stop the 100 press, and means adapted to control said mechanism and itself controlled by the presence of the paper, said means comprising a member arranged to be moved in a plane 105 transverse of the path of the paper and adapted to be rendered inoperative by the absence or the clogging of the paper.

6. In combination with the paper feeding device of a printing press, mechanism normally arranged to automatically stop the press and means adapted to control said mechanism and itself controlled by the presence of the paper, said means comprising a member adapted to be swung into the path 110 of travel of the paper and across such path after the paper has passed, to engage the stop mechanism and thereby render it inoperative when the paper is feeding properly.

7. In combination with the paper feeding device of a printing press, mechanism for automatically stopping the press, and means adapted to control said mechanism and comprising a swinging detent adapted to be 115 oscillated into the path of travel of the paper and governed in its control of said mechanism by the action of the paper, said

detent being arranged to act upon said mechanism after the paper has passed if feeding properly.

8. In combination with the paper feeding device of a printing press, mechanism for automatically stopping the press, and means adapted to control said mechanism and itself controlled by the presence of the paper, said means comprising an oscillating arm, and a 10 detent or finger carried by and pivoted on said arm and adapted to be swung independently by contact with a sheet of paper being fed and thereby kept out of cooperation with the stop mechanism temporarily 15 and until the sheet has passed when the paper is running properly or permanently when the paper feed is clogged.

9. In combination with the paper feeding device of a printing press, mechanism normally tending to automatically stop the press, and means adapted to control said mechanism and itself controlled by the presence of the paper, said means comprising an arm whose free end is oscillated in proximity to the paper in its travel, and a 20 detent or finger pivoted to said end of the arm and arranged to be swung into the line of travel of paper when no paper is passing and to coöperate with the stop mechanism 25 to cause its operation and to be swung by the presence of the paper and thereby kept out of coöperation with the stop mechanism until the sheet has passed and to thereupon engage such stop mechanism to interfere 30 with its normal action and prevent stopping of the press.

10. In combination with the paper feeding device of a printing press, mechanism for automatically stopping the press, and 40 means adapted to control said mechanism and itself controlled by the presence of the paper, said stop mechanism tending to operate to stop the machine and including a member acting to interfere with such operation, said means comprising a detent or 45 finger controlling the action of said member.

11. In combination with the paper feeding device of a printing press, mechanism for automatically stopping the press, and 50 means adapted to control said mechanism and itself controlled by the presence of the paper, said stop mechanism tending to operate to stop the machine and including a member acting to interfere with such 55 operation, said means comprising a detent or finger adapted to engage said member and to render the stop mechanism inoperative only when the paper is feeding properly.

60 12. In combination with the paper feeding device of a printing press, mechanism for automatically stopping the press, and means adapted to control said mechanism and itself controlled by the presence of the 65 paper, said stop mechanism tending to op-

erate to stop the machine and including a member acting to interfere with such operation, and located on one side of the line of feed of the paper, said means comprising a 70 detent or finger located on the other side of such line and controlling the action of said member and itself controlled by the presence of paper being fed, said stop mechanism being arranged to stop the machine in case of non-interference of said member by 75 said detent.

13. In combination with the paper feeding device of a printing press, mechanism for automatically stopping the press, and means adapted to control said mechanism 80 and itself controlled by the presence of the paper, said stop mechanism tending to operate to stop the machine and including a member acting to interfere with such operation, and located on one side of the line of 85 feed of the paper, said means comprising a detent located on the other side of such line, said member being normally non-interfering but arranged to be engaged by said detent and rendered interfering whenever the 90 paper is feeding properly.

14. In combination with the paper feeding device of a printing press, mechanism for automatically stopping the press, and means adapted to control said mechanism 95 and itself controlled by the presence of the paper, said stop mechanism tending to operate to stop the machine and including a trigger, ratchet and pawl and a disk to interfere with the action of the pawl which 100 normally tends to trip the trigger, and said means comprising a detent or finger adapted to coöperate with said disk to prevent operation of the stop mechanism when paper 105 is being fed but to permit such operation when the paper is not being fed or is clogged.

15. In combination with the paper feeding device of a printing press, mechanism for automatically stopping the press, and 110 means adapted to control said mechanism and itself controlled by the presence of the paper, said stop mechanism tending to operate to stop the machine and including a 115 trigger, ratchet and pawl and a disk to interfere with the action of the pawl which normally tends to trip the trigger, such disk being normally held with a yielding pressure to a non-interfering position, and said means comprising a detent adapted to engage said disk and partially rotate it to an interfering position after a sheet of paper 120 has passed.

16. In combination with the paper feeding device of a printing press, mechanism for automatically stopping the press, and means adapted to control said mechanism and itself controlled by the presence of the paper, said stop mechanism tending to operate to stop the machine and including a 125 130

trigger, ratchet and pawl and a disk to interfere with the action of the pawl which normally tends to trip the trigger, such disk being normally held with a yielding pressure to a non-interfering position and provided with a notch, and said means comprising a detent adapted to engage said notch and to partially rotate the disk to an interfering position after a sheet of paper has passed.

17. In combination with the paper feed of a printing press, mechanism for automatically stopping the press and including a movable member normally held with a yielding pressure to a position of non-interference with the stopping action of such mechanism, and means controlled by the paper and arranged to control the movement of said member against such yielding pressure and adapted to move the member to a position of interference when the paper is being fed properly.

18. In combination with the paper feed of a printing press, mechanism for automatically stopping the press and including an oscillating member normally spring pressed to a position of non-interference with the stopping action of such mechanism, and means controlled by the paper and arranged to move said member against such spring pressure to a position of interference when the paper is being fed properly.

19. In combination with the paper feed of a printing press, mechanism for automatically stopping the press and including an oscillating disk which is normally held with a yielding pressure to a position of non-interference with the stopping action of such mechanism, and an oscillating finger controlled by the paper, said finger being in the plane of the disk and arranged to cooperate therewith to cause it to move to a position of interference when the paper is being fed properly.

20. In combination with the paper feed of a printing press, mechanism for automatically stopping the press, and including an oscillating disk which is normally held with a yielding pressure to a position of non-interference with the stopping action of such mechanism, said disk being mutilated to provide a notch or shoulder 81, and an oscillating finger controlled by the paper, said finger being movable in the plane of the disk and arranged to contact said shoulder and to move the disk to a position of interference when the paper is being fed properly.

21. In combination with the paper feed of a printing press, mechanism for automatically stopping the press, and including an oscillating disk which is normally held with a yielding pressure of non-interference with the stopping action of such mechanism, said disk having a hook portion 80,

and an oscillating finger controlled by the paper and movable in the plane of the disk, said finger having a hook portion 76 adapted to engage said portion 80 in event of absence of paper to thereby move the disk from an interfering position.

22. In combination with the paper feed of a printing press, mechanism for automatically stopping the press, and including two members 79 and 87 oscillating in parallel planes, the movement of member 87 causing the stopping action of such mechanism, an oscillating pawl adapted to coöperate with both of said members but normally kept from coöperation with member 87 by the other member 79, and an oscillating finger controlled by the paper and movable in the plane of member 79, said finger being arranged to contact and oscillate said member 79 to keep the pawl out of operation with respect to member 87.

23. In combination with the paper feed of a printing press, mechanism for automatically stopping the press, and including a rock shaft and two disks 79 and 87, the former being loosely mounted thereon and the latter secured thereto, an oscillating pawl coöperating with the edges of both disks but normally kept from coöoperating with disk 87 by the other disk, and an oscillating finger arranged to control the movements of disk 79 to move the same to an interfering position with respect to the pawl and disk 87 whenever the paper is feeding properly.

24. In combination with the paper feed of a printing press, mechanism for automatically stopping the press, and means for controlling said mechanism and itself controlled by the paper, said means comprising an oscillating arm, yielding driving connections therefor having a yielding lost motion, a finger pivoted on said arm and adapted to be swung into the path of paper feed, said finger being arranged to coöperate with the stop mechanism.

25. In combination with the paper feed of a printing press, mechanism for automatically stopping the press, and means for controlling said mechanism and itself controlled by the paper, said means comprising an oscillating arm, a second oscillating arm adapted to be driven, a spring driving connection between these arms, a finger pivoted on said arm and adapted to be swung into the path of paper feed, said finger being arranged to coöperate with the stop mechanism.

26. In combination with the paper feed of a printing press, mechanism for automatically stopping the press, and means for controlling said mechanism and itself controlled by the paper, said means comprising an oscillating arm, a rock shaft on which said arm is loosely mounted, a second arm

secured to said shaft, a spring driving connection between these arms, a finger pivoted on said arm and adapted to be swung into the path of paper feed, said finger being arranged to coöperate with the stop mechanism.

27. In combination with the paper feed of a printing press, mechanism for automatically stopping the press, and means for controlling said mechanism and itself controlled by the paper, said means comprising an oscillating arm, a finger pivoted on said arm and adapted to be swung into the path of paper feed to coöperate with the stop mechanism, and a stop for limiting the movement of the finger with respect to its arm.

28. In combination with the paper feed of a printing press, mechanism for automatically stopping the press, and means for controlling said mechanism and itself controlled by the paper, said means comprising an oscillating arm, a finger pivoted on said arm and adapted to be swung into the path of paper feed to coöperate with the stop mechanism, and a pin and slot stop device for limiting the movement of the finger with respect to its arm.

29. In combination with the paper feed of a printing press, mechanism for auto-

matically stopping the press, and means for controlling said mechanism and itself controlled by the paper, said means comprising an oscillating arm and a finger pivoted at one side of its center of gravity whereby its outer end will tend to move upwardly across the path of paper feed, said finger being arranged to coöperate with the stop mechanism.

30. In combination with the paper feed of a printing press, mechanism for automatically stopping the press including a rock shaft 65 and two members 79 and 87 thereon, the movement of the latter of which causes the stopping action of such mechanism, an oscillating pawl adapted to coöperate with both of said members but normally kept from coöperation with member 87 by the other member, a second rock shaft 67, said two shafts being on opposite sides of the path of feed, means for rocking the shafts in unison, an arm mounted upon shaft 67 and oscillated thereby, and a finger pivoted upon said arm and arranged to coöperate with said member 79.

KARL F. KIRKMAN.
